UNITED STATES PATENT OFFICE.

STEPHEN J. VAN KUREN, OF CEDAR RAPIDS, IOWA, ASSIGNOR TO J. G. CHERRY COMPANY, OF CEDAR RAPIDS, IOWA, A CORPORATION OF IOWA.

SAFETY-GUARD FOR FACTORY-CHURNS.

1,321,575.

Specification of Letters Patent.

Patented Nov. 11, 1919.

Application filed December 4, 1918. Serial No. 265,283.

To all whom it may concern:

Be it known that I, STEPHEN J. VAN KUREN, a citizen of the United States, residing at Cedar Rapids, in the county of 5 Linn and State of Iowa, have invented certain new and useful Improvements in Safety-Guards for Factory-Churns, of which the following is a specification.

The object of this invention is to provide 10 a safety guard which is especially useful on factory churning as a protection against accidental injury to workmen and others when the churn is in operation.

These churning comprise a revoluble drum 15 of considerable size and provided with doors adapted to be securely fastened in place by suitable devices which project from the drum and may engage the clothing of a workman or other person and result in injury to him.

It is the object of my invention to provide 20 a guard rail of simple and inexpensive construction which will provide an effective guard against accidental contact of a person with the revolving drum. The invention also has for its object to provide a guard which will permit access at all times to the drum for inspecting the contents and for putting in salt and other materials without necessitating any manipulation of the guard 25 and which can be easily adjusted to permit access to the drum for removing its contents and for cleansing and other purposes.

In the drawings I have shown one embodiment of the invention, in which—

Figure 1 is a side elevation illustrating the guard applied to one side of a combined churn and butter worker of large size having two doors;

Fig. 2 is an end elevation, partly in section;

Fig. 3 is a detail view of one section of the guard showing the rail swung to upright position;

Figs. 4 and 5 are detail sectional views of the saddle.

Referring to the drawings, 6 designates the churn, 7 the end supports and 8 the pipe girders which connect the supports and 50 form therewith the frame in which the drum and its operating mechanism are supported.

Arms 9 are fastened at suitable intervals on the pipes 8 and are provided with projecting end clamps 10 in which the posts

11 are mounted. These posts project upwardly in an angular direction to about the plane of the axis of the drum and as many posts may be provided as found necessary or desirable. In a large churn, such as illustrated in the drawings, three posts are preferable and in a smaller churn two posts will be sufficient. In the construction illustrated in the drawings, a sleeve 12 is pivotally mounted at 13 upon each of the outer posts 60 and a saddle 14 is mounted on the center post. The guard rail consists of two parts 15 which are adapted to slide in the sleeves 12 and each of which extends from an outer post to the inner post. 65 A stop 16 is arranged on each of said rail parts, intermediate of its ends, to limit the outward sliding movement of said part and a stop 17 may also be provided at the outer end of each of said parts 70 to limit the inward sliding movement of said part. The inner end of each of said rail parts is provided with a downward projection or lug 18 which is arranged to engage a recess 19 in the bottom of the saddle to 75 retain the rail parts in fixed position in the saddle and to provide a continuous railing from end to end of the drum.

The guard rail permits access to the doors 20 of the drum in the position illustrated in 80 Fig. 1 to enable inspection of the contents and for putting material into the drum. When it is desired to empty the drum or to have access thereto for cleansing or other purposes, one or both of the guard rail parts 85 may be lifted out of the saddle, slid outward in its pivot sleeve to the limit of its movement and then swung to upright position, as illustrated in Fig. 3.

The invention provides a guard which 90 will prevent workmen and others from accidentally contacting with the drum and thereby constitutes a protection against accidents and injuries therefrom. For a small churn it will only be necessary to provide 100 two posts, one with a pivot sleeve and the other with a saddle, as will be readily understood from the drawings and the foregoing description.

I am aware that changes in the form and 105 proportion of parts and in the details of construction of my invention may be made without departing from the spirit or sacrificing any of the advantages of the invention and I would have it understood that I 110

desire to make all such changes as may be found desirable to adapt the invention to different conditions and for other purposes so far as the same shall come within the scope of the appended claims. I am also aware that the invention may be employed in connection with a great variety of churning and other dairy machinery which it is not necessary to specify in detail, and I desire to have it understood that by the expression "factory churn" I wish to cover all kinds of machines in connection with which the invention may be useful.

I claim:

- 15 1. The combination with a factory churn comprising a frame, of posts mounted on said frame, and a guard rail pivotally and slidably mounted on one of said posts and adapted to be engaged with the other post.
- 20 2. The combination with a factory churn comprising a frame, of posts mounted on

said frame, a sleeve pivotally mounted on one of said posts, a saddle on the other post, and a guard rail slidably mounted in said sleeve and adapted to be engaged with said 25 saddle.

3. The combination with a factory churn comprising a drum and a frame, of posts mounted on said frame in an inclined position and alongside the drum, a sleeve pivotally mounted on the upper end of one of said posts, a saddle having a recess on the upper end of the other posts, a guard rail slidably mounted in said sleeve, a stop on said rail for limiting its sliding movement 30 in the sleeve, and a projection on said rail to engage the recess in said saddle.

STEPHEN J. VAN KUREN.
